DELBERT D. HALDEMAN, OF ABERDEEN, SOUTH DAKOTA.

HOSE-CO尤LING LOCK.

1,249,074.

Specification of Letters Patent.

Patented Dec. 4, 1917.

Application filed November 3, 1916. Serial No. 129,402.

To all whom it may concern:

Be it known that I, DELBERT D. HALDEMAN, a citizen of the United States, residing at Aberdeen, in the county of Brown 5 and State of South Dakota, have invented new and useful Hose-Coupling Locks, of which the following is a specification, reference being had to the accompanying drawings and to the letters and figures of reference marked thereon.

This invention relates to the type of hose-coupling that comprises two counterpart coupler heads of the class that is used on the ends of air-brake, air-signal and steam-heating pipes on railway cars, for connecting the pipes of the different cars together, each coupler head being connected to the pipe by means of a section of hose, the coupler heads being connected together in 15 a well known manner; the invention having reference more particularly to devices for locking the coupler heads together to prevent leakage at the coupling joint during 20 operation of the railway trains.

An object of the invention is to provide a simple and convenient hose-coupling lock that may be cheaply constructed and which shall be efficient to prevent the sections of 25 hose from buckling up and causing leakage when the slack in the train runs in and out during movement of the cars; another object being to provide an efficient lock for hose-couplings that will permit the coupler heads to pull apart without damage to the 30 parts in case the cars become uncoupled, which locking device shall be of such construction as to be durable and economical in use and not be a hindrance in the operations 35 of connecting or disconnecting the coupler heads but rather facilitate such operations.

With the above-mentioned and other objects in view the invention consists in a pair of counterpart coupler heads provided each with an improved locking device and also a 40 notch or recess to receive the device of the companion coupler head; the invention consisting also further in the novel parts and combinations and arrangements of parts as hereinafter particularly described and further defined in the accompanying claim.

Referring to the drawings,—Figure 1 is a side view of a complete hose-coupling, the sections of hose being fragmentary; Fig. 2 is a perspective view of the improved locking device; Fig. 3 is a front view of one of

the coupler heads; Fig. 4 is a rear view of the coupler head; Fig. 5 is a longitudinal section approximately on the line V—V on Fig. 1; Fig. 6 is an end elevation of the coupler head, and Fig. 7 is a reproduction of a portion of Fig. 5 showing one of the two coupler heads alone.

Similar reference characters on the different figures of the drawings indicate corresponding elements or features of construction herein referred to.

In the drawings the numerals 1 and 1' indicate two sections of air-brake hose to each of which in common practice a coupler head of well known construction is secured, the 45 coupler heads being identically alike but are arranged in relatively reversed order and respectively comprise body portions 2 and 2' having shank portions 3 and 3' that are directly connected to the hose sections, 50 the heads having also elbow portions 4 and 4' provided with joint portions 5 and 5' in which are the orifices of the ducts that extend through the head, the joint portions 55 having gaskets 6 and 6' therein that are 55 brought together when the two heads are coupled together. The ends of the heads have, respectively, suitable projections 7 and 7' that extend from the elbows adjacent to the joint portions, the backs of the projections having ribs 8 and 8' thereon. The 60 body portions have arms 9 and 9' on the fronts thereof that have projections 10 and 10' behind which to receive the ribs 8 or 8' of the companion head and have also ribs 65 11 and 11' on the inner side thereof to be engaged by the rib 8 or 8' to secure the 70 heads together. The projections 10 and 10' have ears 12 and 12' on their normal lower ends respectively and the body portions have 75 ears 13 and 13' respectively on their lower portions, a stop pin 14 being secured to the ears 12 and 13, a stop pin 14' being secured to the ears 12' and 13' to be engaged by the 80 projections 7 or 7' when the heads are properly coupled together. The body portions 2 and 2' are curved and in order to connect the heads together their ends are turned upward to permit the gaskets to be brought together, after which the heads are turned 85 downwardly with the gaskets connected together until the projections 7 and 7' are brought behind the projections 10' and 10 respectively and stopped against the stop 90 pins, in which arrangement the heads are 95 100 105 110

connected together but may be forcibly pulled apart when the train breaks, as is well known.

For the purposes of the invention the front 5 of the arm 9 is provided with hinge ears 15 and 16, the arm 9' being provided with similar ears 15' and 16' that extend along the front of the projections 10 and 10' respectively. A pivot 17 is connected to one 10 pair of ears, a similar pivot 17' being connected to the other pair of ears. Each coupler head is provided with a lock bar to engage the companion head, the lock bar being in the form of a lever that is connected between 15 its ends to the pivot 17 between the ears 15 and 16 so as to constitute a locking portion 18 and a lever arm 19 that has an angular portion 20 so that the lever portion extends along the exterior of the hose section 1, the locking portion 18 normally extending against the projection 10 and a suitable distance beyond the projection. The 20 companion lock bar is connected to the pivot 17' and has a lock portion 18' and also a lever 19', the lock portion being normally in contact with the projection 10'. The lock bars are yieldingly held in normal position by means of springs 21 and 21' respectively which preferably are coiled, one spring being seated in a socket 22 formed in the arm 9 and another socket 23 formed in the lever 19 adjacent to the pivot 17, the spring 21' being seated in a socket 22' formed in the arm 9' and also in a socket 23' formed in the lever 19'. The back of the projections 7 and 7' have ribs 24 and 24' thereon respectively, the ribs preferably being circular and extending about the curved exterior of the elbow portions 4 and 4' respectively; said 35 ribs having recesses or notches 25 and 25' therein respectively, the notch 25' being adapted to receive the lock portions 18, the recess 25 being adapted to receive the lock portion 18', so as to prevent the heads from 40 being accidentally turned upward as is done when uncoupling the heads one from another.

In practical use the workman when grasping the hose sections in the customary manner to couple the heads together, conveniently presses the levers 19 and 19' against the hose sections which retracts the lock portions 18 and 18' and permits the heads to be coupled in the customary manner, the

levers being released when the heads are 55 connected and the lock portions being permitted to enter the recesses or notches designed to receive them. During the movement of the train of cars, as the slack in the draw bar connections runs in or out, the 60 tendency is to swing the house couplings and jerk them upwardly and thus cause leakage at the joint, as is well known, the couplings in normal position being suspended approximately as illustrated in Fig. 1 in which 65 position the couplings are maintained by means of the locks as hereinbefore described. In case the car couplers become disconnected, the hose coupler being connected together, the locking bars permit the coupling heads to be forcibly pulled apart without causing damage since the locking portions slip away longitudinally from the recesses or slots of the companion heads. 70

Having thus described the invention, what 75 is claimed as new is—

In a hose-coupler lock, the combination with a coupler head comprising a body portion and a continuing elbow having an orifice with a gasket therein, and an end projection on the elbow adjacent to one side of the orifice, the back of the projection having a locking rib thereon, of an arm on said body portion having two projecting ears on its front end and having also a socket between the planes of the ears, the arm being beyond the opposite side of said orifice and having a projection with a rib on its back to engage the locking rib of a companion coupler head, the front of the arm projection being flat, a locking bar pivoted to said ears and extending along the flat front and beyond the end of said arm projection, the locking bar having a relatively long lever arm provided with a socket in its rear side, the lever arm having a laterally-extending handle portion, a spring seated in said two sockets, and a circular rib on the back of said end projection and having a transverse recess in its front portion adapted to laterally receive the locking bar of a companion coupler head. 95

In testimony whereof, I affix my signature in presence of two witnesses.

DELBERT D. HALDEMAN.
